CLAIM

The ornamental design for a notebook with sheets for packaged products, as shown and described.

DESCRIPTION

FIG. 1 is a perspective view of a first embodiment of a notebook with sheets for packaged products showing our new design;

FIG. 2 is a top plan view of FIG. 1;

FIG. 3 is a left side view of FIG. 1;

FIG. 4 is right side view of FIG. 1;

FIG. 5 is front view of FIG. 1;

FIG. 6 is back view of FIG. 1;

FIG. 7 is a bottom plan view of FIG. 1;

FIG. 8 is a perspective view of FIG. 1 in an open configuration;

FIG. 9 is a perspective view of FIG. 1 in another open configuration;

FIG. 10 is a perspective view of FIG. 1 in another open configuration;

FIG. 11 is a perspective view of a second embodiment of a notebook with sheets for packaged products showing our new design;

FIG. 12 is a top plan view of FIG. 11;

FIG. 13 is a left side view of FIG. 11;

FIG. 14 is right side view of FIG. 11;

FIG. 15 is front view of FIG. 11;

FIG. 16 is back view of FIG. 11;

FIG. 17 is a bottom plan view of FIG. 11;

FIG. 18 is a perspective view of FIG. 11 in an open configuration;

FIG. 19 is a perspective view of FIG. 11 in another open configuration; and,

FIG. 20 is a perspective view of FIG. 11 in another open configuration.

The broken lines are directed to environment and are for illustrative purposes only; the broken lines form no part of the claimed design.

1 Claim, 20 Drawing Sheets
